UNITED STATES PATENT OFFICE.

GEORGE H. BENEDICT, OF CHICAGO, ILLINOIS.

MEANS FOR ETCHING PLATES OR THE LIKE.

1,176,024.

Specification of Letters Patent. Patented Mar. 21, 1916.

Application filed October 27, 1910. Serial No. 589,317.

To all whom it may concern:

Be it known that I, GEORGE H. BENEDICT, a citizen of the United States, residing at Chicago, in the county of Cook and State 5 of Illinois, have invented certain new and useful Improvements in a Means for Etching Plates or the like, of which the following is a description.

My invention relates to novel apparatus 10 for carrying out the etching process, and has among its objects, the improvement in the art of etching half tone plates, or the like, with the least loss of detail, at the same time holding the greatest possible 15 smoothness of the etched out parts in order that the side walls will lend themselves to faithful duplication, and the production of a simple, durable, satisfactory and more efficient apparatus for carrying out the etching process.

By the employment of the herein described improvements in the art and apparatus, a finer, sharper and more satisfactory finished product is produced, at a low cost 25 of operation and maintenance and with a great degree of uniformity in quality.

To this end my invention consists in the novel construction, arrangement and combination of parts herein shown, described 30 and more particularly pointed out in the claims.

In the drawings, wherein like reference characters indicate like or corresponding parts, Figure 1 is a sectional view of a portion 35 of the device taken substantially on line 1—1 of Fig. 3. Fig. 2 is a sectional view of the same taken substantially on line 2—2 of Fig. 1. Fig. 3 is a sectional view taken substantially on line 3—3 of Fig. 1. Fig. 4 is a top plan view of the complete 40 machine, and Fig. 5 is a side elevation of the same.

By my improved method the plate to be etched is alternately subjected to the action 45 of an etching fluid and free aeration by gently manipulating the bath to effect a delicate laving or washing of the face of the plate. The bath is kept in circulation by natural means, and the greatest aeration 50 of the plate is attained. This is in contradistinction to the spraying, splashing,

atomizing, or other violent agitating principles heretofore used in the etching processes carried out by other etching processes or machines.

55

More specifically, my improvement in the art consists in supporting the plate to be etched face downward over and in proximity to a bath of suitable etching liquid, and then uniformly manipulating the liquid 60 to raise the level of the same sufficiently to cause it to come into contact at intervals with the plate. The liquid is preferably manipulated so as to produce substantially a wave of etching liquid that gently and 65 uniformly rises and approaches to contact with the plate alternately from end to end at a substantially right angle to the face and at a velocity or flow best suited for the kind of plate to be etched. The preferred 70 apparatus for accomplishing this comprises a suitable receptacle for containing the liquid, a plate support approximate the liquid, and a movable transverse mid-feather or head, over the top of which the 75 liquid passes similar to water over a dam, except that in this case the mid-feather or head is moved to produce the flow. Suitable means are also preferably provided to direct the flow of the liquid upon the plate 80 and to increase the proportion of liquid that would normally travel upwardly at right angles to the face of the plate.

Referring to the drawings, in which the preferred form of apparatus is shown for 85 carrying out the process, 1 is a receptacle or bath container, provided with suitable legs 2 and frame part 3, or their equivalents, and containing a suitable etching liquid. The plate 5 to be etched, which is shown in 90 dotted lines in the drawings, is suitably supported by plate supports 6, or their equivalents. The plate supports may be supported by a ledge 9 at each end of the receptacle, and are preferably adjustable relative to 95 each other, so as to carry different sizes of plates. As shown, the plate supports are shouldered as at 7 and recessed as at 7¹, so as to retain the plates in position. At each end of the receptacle 1 also preferably position 100 a splash board 9¹, which prevents washing or splashing of the etching liquid when ma-

nipulated. Within the receptacle 1 is a movable or reciprocating partition 10, which extends with its upper edge substantially proximate the plate face to be etched. The partition 10, which may be termed a mid-feather, a partition, a weir, or a head, substantially divides the receptacle and contents fluid into a plurality of parts, and may be made of any suitable material, and of such length and depth as may be desired. The mid-feather, or head, 10 is carried by a pair of supports 14, which may be connected by a cross-bar 15 at the top to afford strength and rigidity. The supports 14, may be carried by riders 16¹, arranged on the upper edges of the receptacle sides, or by guide rods 16, recessed in the sides of the receptacle, and which support coöperating grooved members 18¹, carried by the arms 18, which are secured to the end of the cross-bar 14. In operation the mid-feather and its supports are reciprocated in the receptacle, as hereafter described. If desired, the mid-feather 10 may be provided with deflectors 11—11, extending transversely on each side, so that as the mid-feather is moved back and forth the liquid at the bottom of the receptacle is deflected upwardly. I also preferably provide a deflector 12 on each side of the mid-feather 10, same being spaced therefrom as at 13, the purpose of the same being to coöperate with the deflectors 11 and increase the normal flow of fluid up the advancing face of the mid-feather 10 and against the plate as the mid-feather is moved back and forth. The liquid level is indicated by the numeral 4, and as shown, the mid-feather being at one end of its travel the levels are substantially as shown for that position. When, however, it is returned to the other side, the liquid on the advancing side rises and passes through the space 13, and over the mid-feather or head, at the same time contacting with the face of the plate, substantially at a right angle thereto, thoroughly and gently laving or washing the plate face. While some liquid may pass over the top of the advancing deflector 12, the greater part is directed upwardly against the face of the plate through the opening 13, as described. If desired, an additional manipulator 17 may be arranged on each side of the mid-feather to more thoroughly stir or manipulate the bath. It should be understood that I do not wish to be understood as confining myself to the use of the deflectors 12—12 or 11—11, as the same results would be obtained to a more or less degree without them, or with their equivalents.

Any suitable means may be provided for reciprocating the head, a very simple arrangement being shown. Referring particularly to Figs. 4 and 5, levers or arms 19 are secured on each side of the frame by bolts 21, and pivotally connected at 20 to arms

23, the arms 23 being pivotally connected to the extended parts 18 of the cross-bar 15. The levers 19 are connected by a bolt or rod 25, to which is secured an arm or connecting bar 24, the opposite end of 24 being secured to a worm wheel 27 by a bolt 26, or their equivalents. The worm wheel may be operated by a worm 28, driven by a motor 29. As is obvious, as the worm wheel is rotated, the partition is moved back and forth under the plate in the receptacle. It will be noted that with the reciprocating mechanism shown, the bars 23 have a direct pull or push on the head at the beginning and end of the head's travel. It is of course understood that any other equivalent mechanism for reciprocating or moving the head, either mechanically or manually, may be employed.

In operation, the plate 5 is positioned on the plate supports face downward over the etching liquid. The head 10 is then reciprocated or moved back and forth for the required time, in the etching fluid, which is raised or forced up through one of the spaces 13, depending upon the direction of travel of the head, and contacts along the face of the plate alternately from end to end. The fluid thus changes from one side of the head to the other, more or less of it coming in contact and acting upon the plate as it changes. In operation the head is preferably so moved that the laying is uniform and comparatively gentle. The results secured by this process and with the apparatus described, are remarkable on account of the smoothness of the etched portions of the plate, because they show no appreciable roughness under moderate magnification. This is of no small importance where the plates are to be duplicated by electrotyping or stereotyping, etc. The very smooth etched surfaces indicate that the material is removed in very small particles, much smaller than when the surfaces are left in relatively rough condition. This must of necessity render small detail and hold accurate dot shapes and sizes more faithfully, and is undoubtedly due to the gentle manipulation or wave motion of the liquid.

The apparatus is exceedingly simple, there being no delicate parts to deteriorate, break or become clogged, or rapidly moving or revolving parts to keep in working condition, so that as a consequence there are no expensive repairs to be incurred. The power required to operate the machine is low, and therefore the total cost of operation is exceedingly economical. The etching liquid may be more efficiently used, and as there is no aeration of the liquid, fumes are scarcely noticeable. The working conditions remain more uniform than usual, and therefore a greater degree of uniformity in the quality of the work is secured.

Having thus described my invention, it is obvious that various immaterial modifications may be made in the same without departing from the spirit of my invention, 5 hence I do not wish to be understood as limiting myself to the exact method, or form, arrangement, construction or combination of parts herein shown and described, or uses mentioned.

10 What I claim as new and desire to secure by Letters Patent is:—

1. A device of the kind described, comprising a liquid receptacle, means for supporting a plate therein in proximity to an 15 etching liquid bath, and means for manipulating the bath within the receptacle to produce a single wave extending across the plate and contacting therewith, and traveling back and forth from one end of the 20 plate to the other.

2. A device of the kind described, comprising an etching liquid bath container, means for supporting a plate to be etched face downward above and without the bath 25 with its face in proximity to the normal level of the etching liquid bath and means arranged in the bath and movable back and forth therein below the plate, for manipulating and gently raising a portion of the bath to produce a wave of a height whereby the crest of the wave will contact with the underside of the plate.

3. A device of the kind described, comprising an etching liquid bath, a plate support 30 arranged in proximity to said bath, and means for manipulating said bath to produce a gentle flow of etching fluid at substantially a right angle to the face of the plate from edge to edge thereof and 40 back and forth against the plate from end to end.

4. A device of the kind described, comprising an etching liquid bath and means for containing the same, means for supporting a plate entirely without and above 45 the normal level of said bath, and reciprocating means arranged in the bath for manipulating said bath to gently raise the same in contact with the plate.

50 5. In an etching machine, an etching liquid bath and means for containing the same, a plate support arranged within said containing means above the normal level of the bath, whereby the plate is normally 55 supported without the bath, and means arranged within said containing means and movable back and forth therein for gently raising a portion of the bath in contact with the plate alternately from end to end 60 thereof.

6. An etching machine, comprising a receptacle containing an etching liquid, means for supporting a plate above said liquid, and means for manipulating said fluid and directing the same against said plate, consist-

ing of a movable partition arranged within the receptacle and extending from side to side and from the bottom to proximate the face of the plate, and means for moving said partition.

70

7. In a device of the kind described and in combination, a receptacle containing an etching liquid, means for supporting the plate to be etched above and in proximity to said liquid, and means for deflecting said liquid against the face of said plate, said means comprising a substantially vertically disposed agitator extending transversely the receptacle and fitting proximate the opposite sides and the bottom, with the upper edge 80 spaced, but in proximity to said plate face, and means for uniformly reciprocating said agitator.

8. In a device of the kind described and in combination, a receptacle containing an 85 etching liquid and means for supporting a plate face downward above said liquid, in combination with means for uniformly directing the liquid against said plate face at substantially a right angle thereto, comprising a movable head arranged within the receptacle dividing the liquid into a plurality of parts.

9. An etching machine comprising a receptacle containing a suitable etching fluid, 95 a plate support and fluid manipulator, comprising a transversely movable partition arranged within the receptacle, means for reciprocating said partition, and means for increasing the normal upward flow of liquid 100 parallel to the advancing side of the partition.

10. An etching machine comprising a receptacle containing a suitable etching fluid, 105 a plate support and a movable head arranged between two sides of the receptacle and extending from the bottom to proximate the face of the plate to be etched, said head provided with a deflector arranged on each side thereof proximate the lower edge, and means for reciprocating said head.

11. An etching machine comprising a receptacle containing a suitable etching fluid, a plate support and a movable partition arranged between two sides of the receptacle 115 extending from the bottom to proximate the face of the plate to be etched, said partition provided with a deflector arranged on each side thereof proximate the upper edge and spaced therefrom, and means for moving said partition.

12. An etching machine comprising a receptacle containing a suitable etching liquid, a plate support and a movable partition arranged between two sides of the receptacle 125 extending from the bottom to proximate the face of the plate to be etched, said partition provided with an auxiliary agitator extending at an angle thereto at each side thereof, and means for moving said partition.

130

13. An etching machine comprising a receptacle containing a suitable etching liquid, a plate support and a movable head arranged between two sides of the receptacle and extending from the bottom to proximate the face of the plate to be etched, said head provided with a deflector on each side thereof, proximate the lower edge, and with a deflector on each side thereof, proximate the

upper edge, and spaced therefrom, and means for reciprocating said head.

In testimony whereof, I have hereunto signed my name in the presence of two subscribing witnesses.

GEORGE H. BENEDICT.
